UNITED STATES PATENT OFFICE

JOHN O. SIMPSON, OF BRISTOL, CONNECTICUT, ASSIGNOR TO THE E. INGRAHAM COMPANY, OF BRISTOL, CONNECTICUT, A CORPORATION

DESIGN FOR A CLOCK BASE

Application filed December 30, 1929. Serial No. 33,980. Term of patent 14 years.

To all whom it may concern:

Be it known that I, JOHN O. SIMPSON, a citizen of the United States, residing at Bristol, in the county of Hartford and State of Connecticut, have invented a new, original, and ornamental Design for a Clock Base, of which the following is a specification, reference being had to the accompanying drawing, forming part thereof.

Fig. 1 is a perspective view of a clock base showing my new design; and

Fig. 2 is a top view of the same.

I claim:

The ornamental design for a clock base as shown.

JOHN O. SIMPSON.
